VALVE FOR PNEUMATIC DISPLACEMENT PUMPS

Filed Oct. 6, 1927

UNITED STATES PATENT OFFICE

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY

VALVE FOR PNEUMATIC-DISPLACEMENT PUMPS

Application filed October 6, 1927. Serial No. 224,380.

This invention relates to well pumps, but more particularly to an automatic well pump having a tank in the well which fills with liquid, such as oil, and then discharges, and 5 repeats this operation as long as there is sufficient oil or other liquid to substantially fill the tank.

One object of the invention is to produce a unitary valve mechanism adapted to be connected to the main pressure fluid supply pipe which will operate automatically controlled by the back pressure created in the tank and supply pipe as the tank is filling. Another object is to enable the automatic mechanism 15 to be set to cut off the supply pressure after a predetermined interval permitted for discharging, and thereafter return the valve mechanism to initial position ready for the next discharging operation.

20 The invention is shown in one of its preferred forms in the accompanying drawings, in which—

Figure 1 is a diagrammatic view partly in vertical section showing an oil well and the 25 automatic pump applied thereto,

Figure 2 is an enlarged detail longitudinal sectional elevation showing the automatic valve mechanism controlling the well tank, with the parts in normal closed position such 30 as would be the case during the time that the tank is filling, and

Figure 3 is a view similar to Figure 2 with the main pressure fluid supply valve open, but the remaining parts in such position that 35 the main valve is ready to close as pressure is built up behind it.

Referring to the drawings, the tank A having the valve B is adapted to be inserted in the well C and is provided with the pressure fluid 40 supply pipe D and the discharge pipe E in the usual manner. Valve mechanism in the casing F is connected to the supply pipe D for automatically discharging the tank after it has substantially filled with liquid. Pressure fluid is supplied to the valve casing through 45 the main pipe G.

The automatic valve mechanism comprises the main control valve H for the pressure fluid supply having a relief port J, in turn 50 controlled by an auxiliary valve in the valve

chamber K. A liquid pressure chamber L is subject to the pressure in the well tank through the passage O connecting with the supply pipe D, and liquid pressure controls the operation of the auxiliary valve in the 55 chamber K.

The main control valve H is preferably subjected to supply pressure on both sides but normally held to its seat by an additional spring pressure due to the heavy spring P held in position by the adjustable screw cap Q. Means are provided, as for instance a port R through the valve H, for permitting supply pressure fluid to pass to the spring 60 pressed side of the valve and in this instance, ports S are provided in the screw cap Q communicating with the relief passage J. When the relief passage J is placed in communication with the atmospheric vent T in the auxiliary valve casing, the main valve H will be 65 automatically raised to supply pressure to the pipe D and when the vent T is cut off by the auxiliary valve, pressure builds up on the spring pressed side of the main valve to automatically close said valve.

The auxiliary valve comprises the main body portion U having the shoulder V, the stem W and the plunger X. A sleeve Y is movable relatively to the plunger and a spring Z of medium tension is located between 70 the head a of the valve body and the valve casing for normally pressing the auxiliary valve downwardly to initial or starting position. The sleeve Y is provided with the spring clip v which holds the sleeve in any position to which it is moved and it is also provided with the vent ports w which are controlled by the plunger X. A perforated plate b is preferably located in the chamber c above 75 the valve plunger X which chamber has a vent d and a spring e heavier than the spring Z bears between the plate b and the adjustable cap f.

The lower enlarged bore g of the auxiliary valve casing contains a plunger h having 80 a spring j which is preferably lighter than either the spring Z or spring e, said spring j being located between the plunger and a screw cap k. This plunger h acts as a valve 85 seating against the valve seat o when in raised 90 position.

position, and cutting off the main passage p leading from the oil pressure chamber L to the auxiliary valve chamber beneath the head a of the valve body. During the time that the 5 valve mechanism is idle the plunger h is held open by the piston a and its associated parts and free communication is therefore established between the chamber L and the valve chamber K . An auxiliary passage q leads 10 from a port r in the bottom of the liquid pressure chamber L to a point beneath the auxiliary valve head a and an adjustable needle valve s controls this port r . A passage t leads from the main oil passage p to a point adjacent 15 the lower end of the plunger h so that the plunger is actuated by oil pressure. A pet cock u connected to the port x communicating with the relief port J is provided for starting purposes. 20 In the operation of the apparatus, let it be assumed that the tank A has been inserted in a well, as for instance, a deep well and the valve mechanism has been adjusted ready for starting the pump. In order to start the 25 apparatus in operation on a new installation, after which the operation is automatic, the pet cock u is opened in order to vent the spring pressed side of the main valve H . The main valve then opens supplying pressure 30 fluid to the tank A and the liquid is discharged through the discharge pipe E to empty the tank. The pet cock u is closed as soon as the operation starts and while the 35 tank is discharging, supply pressure fluid under supply pressure of any desired amount passes through the passage O and forces the oil or other liquid in the chamber L through the main passage p underneath the auxiliary valve head a which immediately and quickly 40 forces the auxiliary valve upwardly, carrying the plunger X and plate b upwardly so that the stem W lies opposite the port w in the sleeve Y which places the relief port J in communication with the vent T and maintains 45 the main valve H open. At the same time liquid pressure flowing through the passage t forces the plunger h upwardly, seating it against the seat o and closing the main liquid 50 passage p . This movement of the plunger h occurs as soon as the plunger is relieved of the weight of the piston a and the passage q is uncovered to prevent the sudden inrush of a considerable amount of liquid through the passage p into the chamber K . Otherwise 55 only a small amount of liquid would remain in the chamber L to flow through the needle controlled port r and, as a consequence, the tank A would be evacuated while only partly filled. Liquid then passes more slowly 60 through the port r controlled by the needle valve s , thence flows through the passage q and continues to more slowly raise the auxiliary valve until the shoulder V forces the sleeve Y upwardly to close off the relief port 65 J . Main pressure fluid then builds up on the

spring pressed side of the main valve H and closes said valve. The time interval controlled by the adjustment of the needle valve s is sufficient for the discharge of the tank A . The position of the auxiliary valve under the 70 conditions specified is shown in Figure 3 in which case the main valve H is indicated just about to close.

After the tank A has been discharged and the main valve H has closed, the drop of pressure in the tank A will permit the springs e and Z to return the auxiliary valve to its initial position. During this movement of the auxiliary valve the liquid is forced from the chamber K into the liquid pressure chamber 80 L through the passage r until the piston a again returns the plunger h to its initial position. By thus depressing the plunger h the passage p will be uncovered and liquid will then pass from the chamber K to the chamber 85 L through the passage p . The spring clip v on the sleeve Y has maintained said sleeve in the position indicated in Figure 3 and as the plunger X is forced downwardly it first closes the ports w in the sleeve and then the plate b pushes the sleeve down to the position indicated in Figure 2 so that the relief port J is maintained closed. The parts are then in 90 position for automatic operation, and as the liquid rises in the tank A the back pressure 95 created in the main supply pipe will pass through the passage O and when this back pressure becomes sufficient as the tank A is substantially filled, the oil or other liquid in the liquid pressure chamber L will be forced 100 downwardly, first through the main liquid passage p to quickly raise the auxiliary valve and open the relief port J and the vent T which permits the main valve H to open and supply pressure for discharging the tank A . 105 The closure of the main passage p by means of the plunger h then causes the auxiliary valve to be actuated more slowly through a given time interval as heretofore explained so that the sleeve Y is actuated to cut off the relief port J after the interval of time sufficient 110 for the complete discharge of the tank A .

I claim:

1. A valve for pneumatic displacement pumps, comprising a casing, a main control valve in the casing, a relief port for said main valve, an auxiliary valve controlling said relief port, a liquid pressure chamber, actuating liquid therein subjected to pressure on the outlet side of the chamber, main and auxiliary liquid passages leading from the liquid pressure chamber to the auxiliary valve, for actuating said valve, means for automatically closing the said main liquid pressure passage after the auxiliary valve has 115 started to move, and thereafter permitting actuating liquid pressure to pass through the auxiliary passage, and means for restricting the flow through said auxiliary passage, whereby the control of the said relief port for 120

the main supply valve is timed for predetermined periods between opening and closing, and means for returning the auxiliary valve to initial position.

5 2. A valve for pneumatic displacement pumps, comprising a casing, a main control valve for the pressure fluid supply exposed to supply pressure on both sides and subject to spring pressure on one side tending to close the valve, a relief port for said main valve communicating with that side of the valve subject to spring pressure, whereby the main valve opens when said relief port is opened and closes by the building up 10 of pressure when said relief port is closed, an auxiliary valve controlling said relief port, a liquid pressure chamber, actuating liquid therein subjected to pressure on the outlet side of the chamber, main and auxiliary liquid passages leading from the liquid pressure chamber to the auxiliary valve for actuating said valve, means for automatically closing the said main liquid pressure passage after the auxiliary valve has started to move, and thereafter permitting actuating 15 liquid pressure to pass through the auxiliary passages, and means for restricting the flow through auxiliary passage, whereby the control of the said relief port for the main supply valve is timed for predetermined periods 20 between opening and closing, and means for returning the auxiliary valve to initial position.

3. A valve for pneumatic displacement 25 pumps, comprising a casing, a main control valve subject to supply pressure on both sides but normally held to its seat by additional spring pressure until the spring pressed side is relieved of supply pressure, a pressure relief port, an auxiliary valve controlling the 30 said relief port, a liquid pressure chamber, actuating liquid therein subjected to pressure on the outlet side of the chamber, a main passage from the liquid chamber leading to the auxiliary valve for actuating said valve, an auxiliary passage from the liquid chamber to the said valve, a needle valve controlling 35 said auxiliary passage, and means for closing the main passage after the auxiliary valve has started whereby the auxiliary valve 40 starts quickly and opens the relief port in order to permit the main control valve to open and thereafter the auxiliary valve travels more slowly and closes the relief port after a predetermined time to permit pressure to build up on the spring pressed side 45 of the main supply valve and close said valve and means for returning the auxiliary valve to initial position.

60 4. A valve for pneumatic displacement pumps, comprising a casing, a main control valve for the pressure fluid supply, a relief port for said main valve, an auxiliary valve controlling said relief port, said auxiliary 65 valve consisting of a body portion, a stem,

a plunger on the stem and a perforated sleeve movable relatively to the plunger, a liquid pressure chamber, actuating liquid therein subjected to pressure on the outlet side of the chamber, a passage leading from the liquid pressure chamber to the body portion of the auxiliary valve for actuating said valve, whereby the plunger stem first opens the relief port and thereafter the plunger sleeve closes the relief port after a predetermined time interval, and means for returning the auxiliary valve to initial position.

70 5. A valve for pneumatic displacement pumps, comprising a casing, a main control valve for the pressure fluid supply, a relief port for said main valve, an auxiliary valve controlling said relief port, said auxiliary valve consisting of a body portion, a stem, a plunger on the stem and a perforated sleeve movable relatively to the plunger, a liquid pressure chamber, actuating liquid therein subjected to pressure on the outlet side of the chamber, main and auxiliary liquid passages leading from the liquid pressure chamber to the body portion of the auxiliary valve for actuating said valve, means for automatically closing the said main liquid pressure passage after the auxiliary valve has started to move, and thereafter permitting actuating liquid 75 pressure to pass through the auxiliary passage, and means for restricting the flow through said auxiliary passage, whereby the plunger stem is first actuated to quickly open the relief port and the plunger sleeve is thereafter actuated by the body portion of the valve to close the relief port after a predetermined time interval, and means for returning the auxiliary valve to initial position.

80 In testimony whereof I have signed this specification.
